UNITED STATES PATENT OFFICE.

WILLIAM A. BRECKON, OF LEE TOWNSHIP, ALLEGAN COUNTY, MICHIGAN.

FRUIT PACKING BASKET.

Application filed August 11, 1926. Serial No. 128,556.

This invention relates to the class of fruit packing devices illustrated in my application for Letters Patent filed April 16, 1926, Serial No. 102,476, the same being an adaptation and in some respects an improvement over features there disclosed and claimed.

The main objects of this invention are:

First, to provide an improved packing device for fruit, vegetables and the like by means of which the packing of fruit is very greatly facilitated.

Second, to provide an improved packing device for fruits, vegetables and the like which enables the packing or handling of the vegetables or fruit with a facing or top layer arranged in selected order with little likelihood of injury or bruising.

Objects pertaining to details and economies of my invention will definitely appear from the detailed description to follow. The invention is clearly defined and pointed out in the claims.

A structure embodying the features of my invention is clearly illustrated in the accompanying drawing forming a part of this application, in which:

Fig. 1 is a perspective view of my improved packing apparatus with the parts in set up or assembled relation.

Fig. 2 is a horizontal section on a line corresponding to line 2-2 of Fig. 1 with the bottom removed.

Fig. 3 is a vertical central section on a line corresponding to line 3-3 of Fig. 2 showing one step in the packing operation.

Fig. 4 is a vertical section showing another step in the packing operation, a basket being inverted over the packing device.

Fig. 5 is a detail view partially in vertical section showing a succeeding step in the packing operation.

Fig. 6 is a plan view of one of the blanks from which a side wall member is formed.

My improved packing device comprises a pair of segmental complementary wall members 1, 1, these members being preferably duplicates. These members in the embodiment illustrated are formed of sheet metal, their lower edges being formed into beads 2 embracing the rod-like segmental hinge members 3 which are connected by pivots 4.

The wall members are provided with overlapping edges 5 and 6, the outer overlapping edge of each member being formed into a bead-like roll 7 in which the latch rods 8

are slidably supported. Loop-like keepers 9 are formed on the other members in alignment with these latch rod supports so that when the latch rods are projected they engage as illustrated in Fig. 1, thus securely retaining the walls in erected position.

The latch rods have hook-like bends at the ends thereof forming hand pieces 10. Tongues 11 are struck from the wall members to engage the ends of the hand pieces thereby retaining the latches in engaged position.

The wall members have portions struck inwardly from the lower ends thereof forming bottom supports 12 which are connected and reinforced by the segmental bars 13. The inverted concave bottom 14 rests upon these supports as shown in Fig. 3, the bottom illustrated having flexible diaphragms 15 secured at its outer edges to the bottom. These diaphragms are adapted to collapse within the bottom as shown in Fig. 4. This bottom feature is shown in the above mentioned application for Letters Patent.

The bottom 14 has a central opening 16 therein adapted to receive the supporting post 17 which engages the disk 18 secured centrally to the flexible diaphragm 15 so that when the parts are assembled in the position shown in Fig. 3 the diaphragm is supported in an upwardly crowned position permitting the packing of the fruit or the like indicated at 19 beginning at the outer circle and filling in toward the center.

After one or more facing layers have been packed a follower disk 20 is arranged on the layer and the packer lifted from the support 12, allowing the diaphragm to collapse to the position shown in Fig. 4. The packer is then filled with the articles to be packed, a basket 21 inverted over the packer and the parts brought to upright position shown in Fig. 5. The latch rods are then released and the packer withdrawn, it being shown in partially withdrawn position in Fig. 5. In withdrawing the operator may, if desired, place a foot upon the bottom, thus preventing the fruit or the like of the facing layer from materially changing its position.

My improved packing device very greatly facilitates the packing or handling of fruits, vegetables or the like and enables the packing thereof with little likelihood of injury to the fruit.

I have illustrated and described my improvements in an embodiment which I have

found very practical. I have not attempted to illustrate other embodiments or adaptations as I believe this disclosure will enable the adaptation of my improvements as may be best suited to the particular requirements.

Having thus described my invention what I claim as new and desire to secure by Letters Patent is:

1. In a basket packing device, the combination of pivotally connected segmental hinge members, segmental complementary walls of sheet metal having their lower edges beaded about said hinge members whereby said wall members are reinforced and pivotally connected, said wall members having overlapping edges when closed, the vertical edge of one of said wall members being beaded to provide a latch rod support and the other having a loop-like keeper struck therefrom to align with said latch support when the wall members are closed, said wall members having portions struck inwardly therefrom and disposed in spaced relation from their lower ends providing ledge members, segmental ledge bars secured to said ledge members, a latch rod slidable in said latch rod support to engage said keeper when the walls are closed, and a bottom removably supported on said ledge.
2. In a basket packing device, the combination of pivotally connected segmental hinge members, segmental complementary walls of sheet metal having their lower edges beaded about said hinge members whereby said wall members are reinforced and pivotally connected, said wall members having overlapping edges when closed, said wall members having portions struck inwardly therefrom and disposed in spaced relation from their lower ends providing ledge members, and segmental ledge bars secured to said ledge members.
3. In a basket packing device, the combination of pivotally connected segmental hinge members, segmental complementary walls of sheet metal having their lower edges secured to said hinge members, said wall members having overlapping edges when closed, one of said wall members having a latch rod support on its overlapping edge and the other having a keeper aligned with said latch support when the wall members are closed, said wall members having bottom supports on their inner sides, a locking rod slidable in said latch rod support to engage said keeper when the walls are closed, and a bottom removably supported on said ledge.
4. In a basket packing device, the combination of pivotally connected segmental hinge members, complementary segmental walls of sheet metal secured at their lower edges to said hinge members, one of said wall members having a latch rod support on its overlapping edge, the other having a

keeper aligned with said latch rod support 65 when the wall members are closed, a latch rod slidable in said support to coact with said keeper, segmental bottom supports disposed on the inner sides of said wall members and a bottom removably supported on 70 said bottom supports.

5. In a basket packing device, the combination of pivotally connected segmental hinge members, segmental complementary walls having their lower edges secured to said hinge members whereby said wall members are reinforced and pivotally connected, said wall members having portions thereof struck 75 inwardly to provide bottom supports, segmental bars secured to said bottom supports, 80 and a bottom removably disposed on said supports.

6. In a basket packing device, the combination of pivotally connected wall segments provided with bottom supports disposed in spaced relation to their lower ends, 85 said wall members having overlapping edges when closed, a latch for securing the walls in closed position, and a bottom removably supported by the said supports.

7. In a basket packing device, the combination of pivotally connected segmental hinge members, segmental complementary walls secured to said hinge members, bottom supports on said wall members, and a bottom removably disposed on said supports.

8. In a basket packing device, the combination of pivotally connected wall segments provided with bottom supports, a latch for securing the walls in closed position, 100 and a bottom removably supported by the said supports.

9. In a basket packing device, the combination of complementary segmental wall members pivotally connected at their lower ends and having overlapping edges when closed, a latch for securing said wall members in closed position, a concave bottom having a central opening therein removably supported on said ledge, a flexible diaphragm secured to said bottom adjacent the periphery thereof, and a support for holding said diaphragm in an upwardly crowned position projecting through said opening in 110 said bottom.

10. In a basket packing device, the combination of complementary segmental wall members pivotally connected at their lower ends, a concave bottom having a central opening therein removably supported on said ledge, a flexible diaphragm secured to said bottom adjacent the periphery thereof, and a support for holding said diaphragm in an upwardly crowned position projecting through said opening in said bottom.

In witness whereof I have hereunto set my hand.

WILLIAM A. BRECKON.
